CLAIM

The ornamental design for a camera, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top front perspective view of a camera showing the claimed design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof; and,

FIG. 8 is an enlarged view of the area shown in dot-dot-dash lines in FIG. 1, for ease of illustration.

The overexposed or faded features depict portions of the camera in which the design is embodied that form no part of the claimed design. Additionally, the dot-dash lines denote the boundary of the claim and form no part of the claimed design.
